X-RAY CASSETTE

Alexander Gobus, Elmhurst, N. Y., assignor to
Sam Tour & Co. Inc., a corporation of New
York

Application May 12, 1952, Serial No. 287,272

2 Claims. (Cl. 250--68)

1

This invention is a new and useful cassette with circular cut-out and quickly mountable sealing means for the edges of said cut-out.

The invention will be fully understood from the following description read in conjunction with the drawing, in which:

Fig. 1 is a plan view with parts in section through one embodiment of my construction;

Fig. 2 is a plan view of one element of the construction shown in Fig. 1;

Fig. 3 is a plan view of another element of the construction shown in Fig. 1 and

Fig. 4 is a vertical section through part of the construction shown in Fig. 1 on the plane indicated by 4-4.

Referring to the drawing 1 designates an X-ray cassette, i. e., a holder for X-ray exposure film which usually consists of a suitable container such as an envelope made of plastic, paper or of more rigid material, such as aluminum, Bakelite, Vinylite, etc. enclosing such film backed by a sheet of metal of high molecular weight, such as a lead. The envelope is ordinarily enclosed in a folder of cardboard which may also carry a sheet of high molecular weight metal on the same side of the film as the first mentioned sheet. This X-ray cassette defines a cut-out portion 2 which may be formed in any convenient manner. It may, for example, be formed by cutting out this section of a rectangular cassette, as available on the market, with scissors or similar tool, but preferably is more conveniently and expeditiously formed by means of the X-ray cassette preparatory device described in my copending application of even filing date, Serial No. 287,271. As is evident from the vertical section, this sealing device comprises collar 3 consisting of the tubular neck portion 4 terminating at one end in the laterally extending, outwardly projecting flange 5. The collar is preferably formed of a material easily permeable to X-rays and similar radiation and may therefore be formed of a plastic or of a low-atomic weight metal, such as aluminum or magnesium. The collar 3 is operated in conjunction with an annulus 6 of similar material, which may be easily secured in the position shown in Fig. 4, operating to snugly secure the cut-out edges of the cassette 1. This is preferably accomplished by means of a coarse thread 7 formed on the outer surface of the tubular portion 4 in combination with a similar and reciprocal thread 8 on the inner edge of the annulus 6. It may alternatively be accomplished by any quickly demountable means such as, for example, bayonet points extending radially outward from the neck 5 in combination with camming surfaces on the

2

annulus, or by an anchor bar passing through two diametrically opposite holes in the neck, or any other suitable way. In operation, as soon as the cut-out has been made in the cassette 1 by any suitable means, the collar 3 is slipped in position and the annulus 6 is threaded into engagement with the tubular section 4 until the collar is firmly secured to the cassette, whereupon the cassette is promptly and effectually sealed against any incident radiation which would fog or expose the film and if the device is made of permeable material, still leave the entire surface of the cassette surrounding the cut-out portion subject to radiographic exposure.

15 I claim:

1. An X-ray cassette with circular cut-out and quickly mountable and demountable sealing means for the edges of said cut-out, comprising an X-ray cassette, a circular opening therein, a neck concentric with said circular cut-out terminating in an annular flange extending outwardly from said neck overlaying the margin of said cut-out on one side of said cassette, an annulus removably embracing said neck overlaying the margin of said cut-out on the other side of said cassette, and quickly demountable means securing said neck, flange and annulus in position, with adjacent faces of said annulus and flange fitting snugly against and sealing the margins of said circular cut-out.

2. An X-ray cassette with circular cut-out and quickly mountable and demountable sealing means for the edges of said cut-out, comprising an X-ray cassette, a circular opening therein, a neck concentric with said circular cut-out terminating in an annular flange extending outwardly from said neck overlaying the margin of said cut-out on one side of said cassette, an annulus removably embracing said neck overlaying the margin of said cut-out on the other side of said cassette, an external thread on said neck, an internal thread on said annulus meshing with said external thread and removably securing said neck, flange and annulus in position with adjacent faces of said annulus and flange fitting snugly against and sealing the margins of said circular cut-out.
